BATHTUB HANGER

William B. Lucke, Wilmette, Ill.

Application March 30, 1936, Serial No. 71,612

3 Claims. (Cl. 4—173)

This invention relates in general to bath tub hangers, but more specifically to means for securing bath tubs to building walls and floors in a manner to prevent leaks at such joining points after settling, which usually results in all building constructions.

Heretofore with devices of this character it has been customary to first secure a hanger to the wall, studding or other support in a building, then set or hang the tub by engaging and resting a flange or rib of the tub upon a flange or projecting portion of the hanger, and then seal the joints between the hanger and tub with an elastic or other suitable sealing material to prevent the formation of cracks or spaces, as well as prevent moisture and water working into the wall, or between the tub and wall or the bracket, and downwardly to the ceiling of the floor below, which leakage results in considerable damage as well as necessitating extensive repairs.

Furthermore, considerable time and labor is necessary to set or so hang the tub, in addition to which, the services of an expert plumber is very often required.

It is one of the objects of the present invention to provide an improved hanger for bath tubs and the like, which may be readily attached and secured to the tub, and the sealing material applied, at the factory, so that the tub, hanger and sealing material may be shipped as a unitary structure, with the result that the same may be properly installed in a building by simply securing the hanger to the building wall, stud, or support, with the assurance that a rigid and waterproof joint will be produced, and relative adjustment of the parts during installation will be dispensed with.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which

Figure 1 is a vertical, transverse, sectional view of one form of bath tub, showing the same secured and held in position by means of a hanger constructed in accordance with the principles of this invention.

Figure 2 is a detail, vertical, sectional view taken on line 2—2, Figure 1, on an enlarged scale.

Figure 3 is a detail, perspective view, of a portion of the hanger.

Figure 4 is a detail, perspective view of a portion of one edge of the tub.

Referring more particularly to the drawing, the tub 10 is provided with the usual flange or rib 11 along the edges thereof, and this flange as well as the tub may be of any desired or suitable construction. In the form of the tub shown in the drawing, the numeral 12 designates an apron or panel at the front of the tub.

An attaching plate or bracket 13 of any desired size and construction is provided with a laterally projecting flange or portion 14, preferably arranged at right angles to the body portion 13, and this flange 14 may be of any desired size and configuration.

The plate may be provided with openings 15 therethrough, and fastening devices 16 in the form of nails, screws, bolts or the like, may be employed for securing the plate in position by attaching the same to uprights or studs 17, or any other suitable support.

The perforations 15 not only lighten the hanger plate, but also serve the purpose of providing a key to hold the plaster in place. Furthermore, the perforations will prevent water from creeping up between the wall plaster and the hanger.

The fastening devices 16 may pass through some of the openings 15 or other openings may be provided for that purpose.

The rib or flange 11 at the edge of the tub in the form of the tub shown, depends below the upper surface of the tub, and the tub is held in position and supported entirely by the studs or uprights 17, and for any desired distance above the floor 18 by the flange or rib resting upon the projecting portion 14 which extends under the edge of the tub.

The space between the attaching or supporting plate or bracket 13 and the flange 14 and the rib of the tub may be filled with any suitable sealing material 19, so as to form a waterproof joint to prevent the water and moisture from working past the edge of the tub and between the edge of the tub and the wall.

The flange or rib 10 is provided with any desired number of apertures 20, passing therethrough, and arranged at any desired position with respect to each other.

Fastening members 21, preferably in the form of bolts, having heads 22 pass through the apertures 20 and also through suitable apertures or openings 23 in the plate or bracket member 13, and nuts or collars 24 are threaded on to the ends of the bolts 21 and preferably rest against the rear face of the plate or member 13. These nuts

or collars 24 co-operate with the heads 22 of the bolts to draw the flange or rib of the tub toward the plate 13 to form a rigid integral structure.

Obviously, the openings 20 in the rib or flange 5 11 may be located in any desired position with respect to the flange or rib.

With this improved construction it will be manifest that the supporting plate or bracket comprising the elements 13 and 14 may be of any 10 desired size and configuration and may be secured to the tub 10, together with the sealing material 19 at the factory, so that the tub and the bracket or supporting plate may be shipped as an integral structure to the place of use, after 15 which the entire structure may be secured in position by securing the plate or bracket 13 to the studs or supports 17.

With this structure it will be manifest that the services of an expert plumber will not be necessary to assemble the parts at the place of 20 use, or to install the mechanism, as the entire structure, that is the tub with the bracket or hanger rigidly attached thereto, and with the sealing material in position, are all fabricated at 25 the place of manufacture.

It is only necessary in installing the structure to properly position the tub and then secure the plate 13 to the studs or uprights 17.

The plates or hangers may be constructed in 30 any desired length and may be suitably arranged with respect to each other and when in position, it will be manifest that the tub will be supported or suspended from the uprights or joists of a building in such a manner that all settling of the 35 tub with respect to the wall or plaster or tiling will be prevented, and which settling generally occurs by shrinking of the floor upon which the tub usually sits, and a shrinking of the floor joists.

Furthermore, all seepage of water between 40 the edge of the tub and the wall will be prevented by the sealing material, and by the use of these hangers, the distribution and arrangement of the same at different points around the periphery, or in the event that the hanger is a continuous 45 structure extending along the sides and ends of the tub or about the periphery, it will be manifest that the tub will be held against any tendency to tilt due to any excessive strain or heavy weight placed upon any one portion of the 50 tub, as the hanger members and the clamping or securing bolts 21 co-operating with the hanger members also serve as a means for preventing tilting of the tub.

While the preferred form of the invention has

been herein shown and described, it is to be understood that various changes may be made in the details of construction and in the combination and arrangement of the several parts, within the scope of the claims, without departing 5 from the spirit of this invention.

What is claimed as new is:—

1. In combination, a bath tub hanger embodying a bracket member having a substantially vertical portion spaced from and extending across 10 the outer face of the rim of a tub and projecting above and below the top and bottom of said rim, said bracket also having a laterally projecting portion extending beneath the lower edge of said rim, sealing material disposed between the outer face and lower edge of said rim and the portions of said bracket that are respectively adjacent said face and edge, and means 15 permanently securing the bracket to the tub rim, adapting the tub and bracket for shipment as a 20 unit, in assembled relation.

2. In combination, a bath tub hanger embodying a bracket member having a substantially vertical portion spaced from and extending across 25 the outer face of the rim of a tub and projecting above and below the top and bottom of said rim, said bracket also having a laterally projecting portion extending beneath the lower edge of said rim, sealing material disposed between the outer face and lower edge of said rim and the portions of said bracket that are respectively adjacent said face and edge, and fastening bolts 30 passing through said rim and a portion of said bracket, adapting the tub and bracket for shipment as a 35 unitary assembled structure.

3. In combination, a bath tub hanger embodying a bracket member having a substantially vertical portion spaced from and extending across 40 the outer face of the rim of a tub and projecting above and below the top and bottom of said rim, 45 said bracket also having a laterally projecting portion extending beneath the lower edge of said rim, sealing material disposed between the outer face and lower edge of said rim and the portions of said bracket that are respectively adjacent said face and edge, a portion of said rim being shaped to form a substantially vertical depending portion, and fastening bolts passing through said depending portion and said bracket permanently 50 securing them together and adapting said tub and bracket for shipment as a unitary assembled structure, said fastening bolts being entirely concealed.

WILLIAM B. LUCKE.
